FREDERICK C. SMITH, OF PORT ARTHUR, TEXAS.

MANDREL.

1,197,774.

Specification of Letters Patent. Patented Sept. 12, 1916.

Application filed June 26, 1913. Serial No. 775,832.

To all whom it may concern:

Be it known that I, FREDERICK C. SMITH, a citizen of the United States, residing at Port Arthur, in the county of Jefferson and 5 State of Texas, have invented certain new and useful Improvements in Mandrels, of which the following is a specification.

This invention relates to new and useful improvements in collapsible mandrels.

10 The object of the invention is to provide a device of the character described upon which may be rolled bolts of flexible material such as manufactured roofing, which is usually made of felt or some other fibrous 15 body, which is saturated with, and whose sides are covered by, water-proof material, such as asphaltum or some other similar material. This mandrel may also be used for rolling other similar materials, such as paper 20 or fibrous goods, which, in their preparation for market, are formed into rolls.

In rolling the goods above described it is usually necessary to use a mandrel, and, unless the mandrel is collapsible, when the roll 25 is formed thereon it is impractical to remove the mandrel, by reason of the fact that the material is so tightly wound thereon that the mandrel cannot be removed, and consequently a separate mandrel would have to 30 be used for each roll.

It is the object of this invention to provide a mandrel which when placed in the rolling machine will be held firmly against collapsing, but after the roll has been removed from said machine the mandrel may 35 be easily collapsed and removed from the roll, and again used for rolling the succeeding rolls, and consequently only one mandrel is necessary and the rolls, when prepared for market, will not be encumbered 40 with a mandrel.

A further feature of the invention resides in the improved construction whereby the mandrel may be easily placed in the rolling 45 machine for the formation of a roll and readily removed therefrom.

With the above and other objects in view the invention has particular relation to certain novel features of construction, operation 50 and arrangement of parts, an example of which is given in this specification and illustrated in the accompanying drawings, wheren:—

Figure 1 is a side elevation of the mandrel in its collapsed position. Fig. 2 is an 55 end view thereof. Fig. 3 is a side elevation

of the mandrel in its expanded position, and as used when the roll is being formed thereon. Fig. 4 is an end view thereof. Fig. 5 is a side elevation of the rolling machine 60 with the mandrel therein, showing a roll of material wound on the mandrel; and Fig. 6 is an end view thereof.

Referring now more particularly to the drawings, wherein like numerals of reference designate similar parts in each of the figures, the numeral 1 refers to the framework of the rolling machine which has alined bearings 2 and 3 arranged, respectively, on each end thereof. The bearing 2 65 is open above, as shown in Fig. 6, and a short shaft 4 normally rests therein. Alined with the shaft 4 on the other side of the machine is a shaft 5 which is rotatably mounted in the bearings 3 and 6, the latter 70 of which is supported upon the upper end of the support 7. This shaft 5 is also slid- 75 able longitudinally in its bearings, and is operatively connected with its driving mechanism or shaft 8, which receives rotation 80 from a suitable motor, not shown. Any preferred form of drive mechanism may be used, and it is not thought necessary to specifically describe the mechanism shown. This mechanism, however, may be readily 85 connected with and disconnected from the motor by means of the clutch 9 in a well-known manner, as, for instance, a hand-lever 9^a having suitable connections 9^b with said clutch. I preferably drive the shaft 5 90 from the shaft 8, by means of a friction wheel or pulley 5^a having driving contact with a grooved friction pulley 8^a, fixed on the shaft 8, said pulley 5^a being feathered to the shaft 5 so that the latter may move 95 lengthwise through said pulley 5^a without displacing the same from the groove of the pulley 8.

The mandrel itself comprises the invention sought to be protected hereby, and said 100 mandrel will now be described.

The numerals 10 and 11 designate, respectively, two bearing members forming the respective heads or ends of the mandrel. These members preferably consist of short 105 stud shafts or cylindrical blocks, formed of metal or some other durable material. To the inner end of one of said heads, shown as being the head 10, is secured a hollow bar or shaft 12, and to the inner end of the 110 opposite head is secured a solid bar or shaft 13, which telescopes within the bar or shaft

12, said shafts being slidable, relative to one another. The bar or shaft 12 has oblong slots 14 in both sides thereof and extending into the hollow thereof, and the said shaft 5 13 has a pin 15 fixed thereto, which projects out through the slots 14. This pin limits the lengthwise movement of the shaft 13 relative to the shaft 12, said movement being limited by the length of the slots 14. A 10 plurality, preferably four, material-supporting members comprising in the present embodiment of the invention, round bars or hollow shafts 16, 17, 18 and 19 are provided, of a length preferably equal to the 15 desired length of the roll to be formed, and these respective bars or shafts are connected at their respective ends to the stub shafts or heads 10 and 11, by means of short links 20, 20, 21, 21, 22, 22, and 23, 23, said links 20 being pivoted at their outer ends to the respective ends of the corresponding bars or shafts, and at their inner ends to said stub shafts 10 and 11. The material-supporting members upon which the roll is formed remain in normally expanded relation during 25 the formation of the roll until the stub shafts 10 and 11 are moved apart and the links above described are operated so as to move the bars 16, 17, 18 and 19 close together, consequently collapsing the mandrel, 30 and permitting easy and ready removal of the completed roll of material. Conversely, a movement of the heads or stub shafts toward each other operates through the links 35 to expand the mandrel into position ready for the formation of a new roll thereupon. In this manner, I have provided a mandrel, the material-supporting members of which are capable of two positions, an expanded 40 position in which the roll of material is formed, and a collapsed position to permit removal of the mandrel from the roll and its use for the formation of other rolls.

The outer ends of the shafts 10 and 11 45 have centrally located sockets 24 and 25 to receive the respective inner ends of the shafts 4 and 5, when the mandrel is in position in the rolling machine and the roll of material is being formed thereon. The shaft 5 50 has a collar 26 fixed thereon, interposed between which and the bearing 6 is a coil spring 27, which tends to force said shaft 5 toward the mandrel and hold the inner end of said shaft in the socket 25, and the inner 55 end of said shaft 4 in the socket 24.

Near the inner end of shaft 5 is a pin 28 60 extending each way from said shaft and fitting into a corresponding transverse groove 29, across the outer end of the head or shaft 11. The pin 28 locks in the groove 29 and forces the mandrel to rotate with the shaft 5. However, any other preferred means for locking these shafts so that they will rotate together may be adopted, such as 65 by making the socket 25 square and shaping

the inner end of said shaft 5 to conform thereto. When the mandrel is in position in the rolling machine the free end of the material 30 is manually rolled around the mandrel, and the shaft 5 then operatively connected with the driving mechanism which operates to rotate the mandrel and wind the roll thereon. When the roll is formed to the desired size it is then grasped manually and forced against shaft 5, which 70 slides back in the bearings 3 and 6 so as to disengage the socket 24 from the inner end of the shaft 4. The outer end of this shaft is hinged as at 31^a to an adjustable support 31, projecting from the corresponding end 80 of the frame 1, and when the inner end of shaft 4 has been disengaged from the socket 24 said shaft may then be lifted out of its bearing 2 and the roll removed from the rolling machine. The mandrel may then be 85 manually collapsed very readily and removed from the roll.

When it is desired to place the mandrel again in the machine for the formation of the next roll, the socket 25 is engaged over the inner end of the shaft 5 and said shaft forced back in its bearings, as before described, and the shaft 4 is then manually swung around into its bearing 2 and its free end brought into alignment with the 95 socket 4 and the push of the coil spring 27 against the collar 26 will force the shaft 5 and the mandrel toward the free end of the shaft 4, and cause said free end to engage in the socket 24, and hold the mandrel expanded. The support 31 may be adjusted toward and from the supporting frame by means of hand screw 32 operable by a hand wheel 32^a upon which hand screw said support 31 is mounted, as shown in Fig. 1, so 100 that mandrels of different lengths may be accommodated to the rolling machine. From the description hereinbefore set forth it is obvious that the material may be wound tightly on the mandrel and thus formed into 110 a compact roll which will thereby be more evenly and compactly formed, and will occupy the smallest amount of space, and when completed the mandrel may be easily and quickly removed therefrom.

While I have shown only one form of my device it is apparent that the mechanical construction thereof may be varied without departing from the principle of the invention, and I desire to reserve the right to 120 alter the mechanical construction thereof, so long as I do not depart from the scope of the appended claims.

What I claim is:—

1. In a device of the class described, the 125 combination of a frame provided with bearings, stub shafts journaled in said bearings, one of said shafts being endwise movable, a spring acting upon the latter shaft, and a mandrel carried by said shafts and compris- 130

- ing a plurality of bars on which a roll of material may be wound and having normally expanded relation while said roll is being wound thereon, two slidably connected members having heads at their outer ends provided with means fitting said stub shafts, and links connecting said slidably connected members with opposite ends of said bars respectively to collapse the bars upon sliding movement of said members and permit the removal of said mandrel from the material when the roll has been wound.
2. A mandrel comprising a plurality of bars upon which a roll of material may be wound and having normally expanded relation while said roll is being wound thereon, and a central mounting device for said bars comprising a tubular shaft and a second
- 10
- 15

shaft slidably fitted therein, the shafts having heads fixed on the outer ends thereof provided with sockets to engage supporting means for the mandrel, and links pivoted to said fixed heads and to the opposite ends of said bars and capable of collapsing the bars upon the sliding movement of the parts of said telescopic shaft to permit the removal of said mandrel from the material when the roll has been wound.

In testimony whereof I have hereunto signed my name in the presence of two subscribing witnesses.

FREDERICK C. SMITH.
